(57) **CLAIM**

The ornamental design for a packaging, as shown and described.

DESCRIPTION

FIG. 1 is a front, top, and left side perspective view of a first embodiment of a packaging showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front, top, and left side perspective view of a second embodiment of a packaging showing my new design.

FIG. 9 is a front elevational view thereof.

FIG. 10 is a rear elevational view thereof.

FIG. 11 is a top plan view thereof.

FIG. 12 is a bottom plan view thereof.

FIG. 13 is a right side elevational view thereof; and,

FIG. 14 is a left side elevational view thereof.

The surface ornamental applied on the environmental structure form part of the claimed design. The evenly-spaced
